SAMUEL K. NESTER, OF GENEVA, NEW YORK, ASSIGNOR, BY MESNE ASSIGNMENTS, TO
FREDERICK JOHN, EDWIN CHINA, AND BURT, BOULTON & HAYWOOD, LIMITED,
OF LONDON, ENGLAND

DISINTEGRATING MILL

Application filed September 29, 1924, Serial No. 740,650. Renewed August 8, 1930.

My invention relates to disintegrating mills, and more particularly to the type of mill having relatively smooth spaced surfaces adapted to move past each other at a high velocity, and in which liquid with particles, liquid or solid, suspended therein is disintegrated in the thin film between the working surfaces.

In the type of mill in commercial use, the outlet is located at the apex of the angle formed by the sloping inner walls or spillways of the outlet chamber. Each sloping wall or spill-way covers approximately half of the bottom of the output chamber. The liquid material in the mill is given a high velocity of rotation, and it was found that this caused collection of treated material in the chamber above the rotor of the mill, so that the materials, whether thin or viscous, did not easily evacuate. The power consumption was found to be greater than mathematical computations would lead one to believe to be necessary.

The difficulty of evacuating the output chamber and consequent piling up of treated liquid in the chamber above the rotor, I have discovered to be the principal source of the power losses. Moreover, the back pressure of the chamber above the rotor caused the treated liquid with the suspended particles therein to be forced up the rotor shaft and into the ball bearings, this often caused the ball bearings to be ruined, necessitating repairing and replacement.

Experiment showed that the high circular motion in the output chamber of this type of mill caused the materials, either light or viscous to be swept over the outlet pipe and strike the reversely inclined surface on the opposite side, and by that surface to be carried up towards the dome. These materials because of the further upward impetus imparted by the reversely inclined surfaces continue to whirl around in a circular motion in the top part of the dome. The direction of motion, of course, is the same as that of the rotor. Any air in the output chamber is forced out through the exit pipe, allowing more material to replace the air expelled, and this action very soon caused the entire out-

put chamber to be filled with whirling liquid. A great increase of power is necessary to perform the work, largely because of the friction of the liquid on the top of the rotor.

An actual test showed that in a very short run materials would rise out of a tube or pipe set vertically in one of the port hole caps in the cover. The height to which the materials would rise depended of course upon operating conditions.

An object of this invention is to reduce the amount of power necessary to operate a disintegrating mill of the type described.

Another object of this invention is to prevent accumulation of treated material in the output chamber

A further object of this invention is to prevent material from getting into the ball bearings supporting the rotor shaft.

Another object of this invention is to provide for preventing splashing of material on to the upper surface of the rotor.

Another object of my invention is to provide the means of the introduction of air into the material in the output chamber thus preventing vacuum or back pressure.

Yet another object of my invention is to show a construction wherein materials will not be accumulated in the input pipe, thus preventing their settling.

With these and other objects in view which may be incident to my improvements, the invention consists in the parts and combinations to be hereinafter set forth and claimed, with the understanding that the several necessary elements comprising my invention, may be varied in construction, proportions, and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a longitudinal sectional view.

taken through the axis of the shaft of the mill.

Fig. 2 is a view in side elevation of the lower portion of the output chamber showing the position of the baffle plate and inclined surfaces in dotted lines.

Fig. 3 is a top plan view of the lower casting of the output chamber such being a section of the line 3—3 of Fig. 1.

Fig. 4 is a longitudinal sectional view showing in detail the position of the baffle plate.

Referring to the drawings for detail description I have shown the mill having a bearing supporting structure or spider 1 in which is mounted a lower bearing 2 of the mill, in which latter is journaled a rotor shaft 3. The supporting spider is screw threaded at 4 to receive screw threaded adjusting member 5 that carries the upper bearing 6 in which the shaft 3 of the mill rotates.

The position of the shaft 3 is determined by adjusting the adjusting member 5 which carries with it the shaft 3. To aid in adjusting, member 5 is provided with micrometer markings (not shown) which co-operate with a pointer 7, to enable the operator to accurately adjust the position of the shaft 3.

Mounted at the lower end of the shaft 3 is a rotor 8, having a frusto-conical working surface 9, and a horizontally projecting lip 10. The rotor 8 is held on the shaft 3 by the nut 11.

The supporting spider 1 is provided with an annular flange 12 which forms with the supporting spider an annular shoulder 13. A cover 14 is provided with an annular shoulder 15 adapted to fit into the annular shoulder 13 on the supporting spider 1. Bolts 16 hold the supporting spider in place on the cover. An annular concave depression 17 is formed on the inside of the cover 14. The interior edge of this annular concave depression is approximately opposite the upper edge of the working surface 9 of the rotor 8.

Adjacent to the top of the rotor 8 the cover 14 is provided with a closely fitting portion 18 lying adjacent to the top surface of the rotor 8 and closely spaced therefrom. Where the shaft 3 passes through the cover 14 there is provided an annular aperture 19, surrounding the shaft 3 and providing an air inlet. A flange 21 around the outer periphery of the cover 14 provides means whereby bolts 22 may hold the cover of the output chamber to the base casting 23, which latter is also provided with flanges 24 for a similar purpose.

The base casting 23 is provided with an interior portion 25, thru which is formed an inlet duct 26 communicating with an upwardly slanted inlet pipe 27. The upper end of the duct 26 communicates with a conical intake chamber 28, terminating at its upper end in a smooth frusto-conical working surface 29 adapted to lie adjacent to the working surface 9 of the rotor 8. The working sur-

face 29 is stationary, and the material fed into the input chamber 28 is adapted to be fed in a thin film between the rotating working surface 9, and the stationary working surface 29. When high velocity is given to the rotor 8 by means of a pulley 31 mounted on the shaft 3 or by any other suitable means, disruptive forces are generated in the film of liquid existing between the stationary and rotating working surfaces.

Integrally formed with the base casting 23 is a spirally inclined web or support 32, whose upper end 33 is approximately level with the discharge end of the stator and rotor working surfaces, and whose lower end 34 lies adjacent an upper end of the outlet duct 35 formed in the casting 23. Joining the upper edge 33 of the spiral inclined surface 32 with the opposite upper end of the output duct 35 is a concave baffle plate 36, which overhangs the outlet 35 and downwardly slopes to the outlet. This baffle plate directs the treated liquid into the outlet and prevents its further rotation around the output chamber of the mill.

In operation the material to be treated is fed in through inlet pipe 27 whose downward slant is made possible by introducing it through the casting 23 at a point adjacent the top 33 of the spiral surface or web 32. This slanting of the feed pipe prevents collecting or settling of solids as is often the case with a horizontal feed pipe. Hence the construction of the base casting with the spiral surface accomplishes a useful purpose in permitting the introduction of the feed pipe at a relatively high point of the spiral so that the pipe may have a downward slant to the input chamber. The material to be treated passes through duct 26 and into input chamber 28 where it is fed out through the film existing between the stator surface 29 and the rotor surface 9. By reason of the close proximity of the surfaces and the velocity of the rotor surface, disruptive forces are generated in the film which disrupt the particles, liquid or solid, suspended in the material treated.

The lip 10 on the rotor prevents any splashing on top of the rotor and tends to throw the material outward horizontally. The lip, however, causes the material to be discharged horizontally, and tends to prevent piling up of material in the top of the output chamber with consequent back pressure and increased power losses.

Splashing is further prevented by the portion 18 of the cover 14 which fits closely adjacent to the top surface of the rotor 8. Since the materials are thrown out by the lip 10 on a horizontal plane air is forced in the same direction thus causing a vacuum at the air inlet 19, whereby air is introduced into the chamber containing the treated material.

The introduced air tends to prevent vac-

uum in the output chamber and acts to prevent any materials from remaining at the top of the output chamber. Moreover, the rush of air around the shaft and the lower bearing tends to keep the lower bearing cold.

This is of material benefit in those instances where hot materials are treated, since the air prevents overheating of the bearing and particularly prevents melting out the grease.

10 Should any treated materials ever back up they will appear through the air opening 19, and the faulty operation of the mill will become at once apparent so that the condition can be immediately remedied.

15 The annular concave shape of the cover 14 causes any materials discharged against the interior of the cover to be quickly delivered to the spiral incline 32, and tends to prevent filling of the output chamber with 20 accumulated treated material with consequent friction losses and possible injury to the ball bearings.

The spirally inclined surfaces and the baffle plate co-operate to direct the material to 25 the outlet and with the mill as shown in the drawings, the rotor is adapted to rotate in counter-clockwise direction. The inclined surface leads or guides the rotating material discharged from the mill continuously towards the outlet 35. The baffle plate 36 arrests the material in its spiral motion and directs it through the outlet. With the construction of the baffle plate and spirally inclined surface it is impossible, under normal 30 conditions, for any material to complete more than one rotation around the interior of the mill after it has passed into the output chamber. The baffle plate prevents filling of the chamber and consequent damage to the lower bearing and loss of power, and the combination 40 of the baffle plate with the spirally inclined surface provides a more efficient means for quickly and thoroughly evacuating the output chamber. It is normally impossible 45 for a vortex of treated material to be formed in the output chamber unless some such contingency occurs as actual stoppage of the outlet pipe.

It must be realized that air introduced into 50 the chamber with the treated material does not cause the material to become creamy as is in the case where air is introduced into the input side of the mill. The materials in the output chamber when thrown on to the spirally inclined surface cause a centrifugal air draft in the output chamber forcing air and materials down the spirally spill-way, and thus the spiral surface tends to increase the amount of air sucked into the output chamber 55 through the air inlet 19.

While I have shown and described the preferred embodiment of my invention, I wish it to be understood that I do not confine myself to the precise details of construction herein set forth, by way of illustration,

as it is apparent that many changes and variations may be made therein, by those skilled in the art, without departing from the spirit of the invention, or exceeding the scope of the appended claims.

I claim:

1. An apparatus for the disintegration of particles, liquid or solid, suspended in a liquid, comprising closely adjacent working surfaces, means to introduce material between the working surfaces, an output chamber having outlet therein, sidewalls for said output chamber, and a baffle plate adjacent such outlet positioned to direct the treated material through the outlet.

2. An apparatus for the disintegration of particles, liquid or solid, suspended in a liquid, comprising closely adjacent working surfaces, means to introduce material between the working surfaces, an output chamber having an outlet therein, and baffle plate overhanging and downwardly sloping to the outlet to direct the treated material there through.

3. An apparatus for the disintegration of particles, liquid or solid, suspended in a liquid, comprising closely adjacent working surfaces, means to introduce material between the working surfaces, an output chamber having an outlet therein, and a baffle plate concavely curved overhanging and downwardly sloping to the outlet to direct the treated material there through.

4. An apparatus for the disintegration of particles, liquid or solid, suspended in a liquid, comprising closely adjacent working surfaces, means to introduce material between the working surfaces, an output chamber having an outlet therein, sidewalls for said output chamber, a spirally inclined surface in said output chamber, and a baffle plate co-operating with the spirally inclined surface to direct the treated material through the outlet.

5. An apparatus for the disintegration of particles, liquid or solid, suspended in a liquid, comprising closely adjacent working surfaces, means to introduce material between the working surfaces, an output chamber having an outlet therein, a spirally inclined surface, and a baffle plate joined at its top to one edge of the inclined surface whereby the treated material is directed to the outlet.

6. An apparatus for the disintegration of particles, liquid or solid, suspended in a liquid, comprising closely adjacent working surfaces, means to introduce material between the working surfaces, an output chamber having an outlet therein, a spirally inclined surface the lower end of which terminates adjacent the outlet, and a baffle plate curved overhanging and downwardly sloping to the outlet, said plate being joined at its top edge to the upper end of the inclined surface.

7. An apparatus for the disintegration of

5 particles, liquid or solid, suspended in a liquid, comprising closely adjacent working surfaces, means to introduce material between the working surfaces, an output chamber having an outlet therein, a spirally inclined surface integrally cast with the output chamber, the lower end of which terminates adjacent the outlet, and a concavely curved baffle plate overhanging and downwardly sloping to the outlet integrally cast with the output chamber.

10 6 8. An apparatus for disintegrating particles, liquid or solid, suspended in a liquid, comprising an output chamber, a member with a stationary working surface, a movable member with a working surface adjacent thereto, means for introducing the liquid in a film between said surfaces and an outwardly extending lip on said movable member adjacent the point of egress of the film to prevent backing up of said liquid in the top of said output chamber.

15 7 9. An apparatus for disintegrating particles, liquid or solid, suspended in a liquid, comprising an output chamber, a member with a stationary working surface, a movable member with a working surface adjacent thereto, means for introducing liquid in a film between the said surfaces, and an outwardly extending annular lip adjacent the point of egress of the film and carried by the movable member to prevent backing up of said liquid in the top of said output chamber.

20 8 10. An apparatus for disintegrating particles, liquid or solid, suspended in a liquid, comprising an output chamber, a member with a stationary working surface, a movable member with a working surface adjacent thereto, means for introducing the liquid in a film between said surfaces, and an outwardly extending annular lip integrally formed with the movable member adjacent the point of egress of the film from the working surfaces to prevent backing up of said liquid in the top of said output chamber.

25 9 11. An apparatus for disintegrating particles, liquid or solid, suspended in a liquid, comprising an output chamber, a stationary member having a frusto-conical working surface, a rotatable member having a frusto-conical surface lying within the first mentioned surface, means for introducing the liquid in a film between said surfaces, and an outwardly extending annular lip attached to the rotatable member and overlying the end of the stationary frusto-conical surface whereby said liquid is prevented from piling up in the top of said output chamber.

30 10 12. An apparatus for disintegrating particles, liquid or solid, suspended in a liquid, comprising a member with a stationary working surface, a movable member with a working surface adjacent thereto, means for introducing the liquid in the film between said

surfaces, and a cover independent of the stationary working surface having a concave annular rounded depression on the inner side thereof into which the working surfaces discharge.

70 13. An apparatus for disintegrating particles, liquid or solid, suspended in a liquid, comprising a member with a stationary working surface, a movable member with a working surface adjacent thereto, means for introducing liquid in the film between said surfaces, and a cover independent of the stationary working surface having an annular concave depression on the inner side thereof, the inner edge of the depression being adjacent the discharge side of the working surface.

75 14. An apparatus for disintegrating particles, liquid or solid, suspended in a liquid, comprising a stationary member with a working surface, a rotatable member with a working surface adjacent the first mentioned surface, means for introducing the liquid in a film between said surface, and a cover independent of the stationary working surface having a portion closely fitting the top side of the rotatable member.

80 15. An apparatus for disintegrating particles, liquid or solid, suspended in a liquid, comprising a stationary member with a working surface, a rotatable member with a working surface adjacent the first mentioned surface, a cover independent of the stationary working surface having a concave depression on the inner side thereof into which the working surfaces discharge, and having a portion closely fitting the top side of the rotatable member.

85 16. An apparatus for disintegrating particles, liquid or solid, suspended in a liquid, comprising a stationary member with a working surface, a rotatable member with a working surface adjacent the first mentioned surface, a cover independent of the stationary working surface having an annular depression on the inner side thereof, the inner edge of the depression being adjacent the discharge side of the working surfaces, and having a portion closely fitting the top side of the rotatable member.

90 17. An apparatus for disintegrating particles, liquid or solid, suspended in a liquid, comprising a stationary member with a working surface, a rotatable member with a working surface adjacent the first mentioned surface, a shaft for the rotatable member, and a cover having an air opening adjacent the shaft and having a portion whose outer edge closely fits the top side of the rotatable member.

95 18. An apparatus for disintegrating particles, liquid or solid, suspended in a liquid, comprising a stationary member with a working surface, a rotatable member with a working surface adjacent the first mentioned sur-

face, a shaft for the rotatable member, and a cover having an air opening entirely surrounding the shaft and having a portion of approximately the same diameter as the top edge of the rotatable member and closely adjacent thereto.

19. An apparatus for disintegrating particles, liquid or solid, suspended in a liquid, comprising a stationary member with a working surface, a rotatable member with a working surface, a shaft for the rotatable member, and a cover having a portion closely fitting the top side of the rotatable member and provided with an air opening adjacent the shaft.

20. An apparatus for disintegrating particles, liquid or solid, suspended in a liquid, comprising a stationary member with a working surface, a rotatable member with a working surface adjacent the first mentioned surface, a shaft for the rotatable member, a cover having an annular depression on the inner side thereof, the inner edge of the depression being adjacent the discharge side of the working surface, said cover having a portion closely fitting the top side of the rotatable member and being provided with an air opening entirely surrounding the shaft.

21. A disintegrating apparatus comprising concentric spaced rotor and stator surfaces, having the peripheries angularly positioned with respect to the vertical in cross section, means to direct the material passing therethrough outwardly in a collecting chamber, means to draw air to fill the vacuum in the collecting chamber created by the introduction of the material therein by centrifugal force of the rotor, and means to deflect the material directed outwardly to the collecting chamber, and downwardly toward the outlet.

22. A disintegrating apparatus comprising concentric, parallel, angularly extending rotor and stator surfaces, having vertical coincident axes, means to introduce material under a head against the bottom face of the rotor for introduction between the rotor and stator surfaces, means carried on the top face of the rotor for directing material passing between the rotor and stator surfaces outwardly into a collecting chamber communicating with an outlet, means to introduce air on the top face of the rotor for filling the vacuum created in the collecting chamber by introduction of the material therein from the rotor, and means to deflect the material directed therein outwardly and downwardly to the outlet.

23. A disintegrating apparatus comprising a stator surface communicating with inlet and outlet chambers, a rotor operating adjacent the stator surface, having one face exposed to the inlet chamber, and means to direct a current of air over the other face of the rotor to prevent contact of the material

passing between the rotor and stator surfaces therewith.

24. A disintegrating apparatus comprising a stator surface communicating with inlet and outlet chambers, a rotor operating adjacent the stator surface, having one face exposed to the inlet chamber, and means to direct a current of air radially over the other face of the rotor to prevent contact of the material passing between the rotor and stator surfaces therewith.

25. A disintegrating apparatus comprising a stator surface communicating with inlet and outlet chambers, a rotor operating adjacent the stator surface, having one face exposed to the inlet chamber, and an air inlet adjacent the other face of the rotor, adapted to admit air radially to the periphery of the rotor to fill the vacuum in the outlet chamber created by the material passing thereto from between the rotor and stator surfaces and to prevent contact of the material therewith.

In testimony whereof I affix my signature.

SAMUEL K. NESTER.
